DESIGN FOR A BOTTLE BREAKING APPARATUS

Frank P. Chagnon and Cyrus N. Snyder,
Los Angeles, Calif.

Application June 14, 1938, Serial No. 77,829

Term of patent 3½ years

To all whom it may concern:

Be it known that we, Frank P. Chagnon and Cyrus N. Snyder, citizens of the United States of America, residing at Los Angeles, in the county of Los Angeles and State of California, have invented a new, original, and ornamental Design for a Bottle Breaking Apparatus, of which the following is a specification, reference being had to the accompanying drawing, forming part thereof.

The figure is a perspective view of the bottle breaking apparatus showing our new design.

The rear and left side of the apparatus is perfectly plain.

We claim:

The ornamental design for a bottle breaking apparatus, as shown and described.

FRANK P. CHAGNON.
CYRUS N. SNYDER.
